DANIEL L. F. CHASE, OF BOSTON, MASSACHUSETTS.

Letters Patent No. 75,523, dated March 17, 1868.

IMPROVEMENT IN STEAM-ENGINE GOVERNORS.

The Schedule referred to in these Letters Patent and making part of the same.

TO ALL TO WHOM THESE PRESENTS SHALL COME:

Be it known that I, DANIEL L. F. CHASE, of Boston, in the county of Suffolk, and State of Massachusetts, but at present a resident of the Kingdom of Great Britain, have invented a new and useful Governor for Steam-Engines, and other purposes, and do hereby declare the following to be a full, clear, and exact description thereof, due reference being had to the accompanying drawings making part of this specification, and in which—

Figure 1 is a front elevation,

Figure 2 a side elevation, and

Figure 3 a vertical and longitudinal section of the said invention.

Figures 4, 5, and 6 represent detached views of the valves and valve-ports hereinafter referred to.

This invention is an improvement in that class of governors known as ball-governors, or those in which the centrifugal force of two balls, fixed upon the extremities of two variable arms, and revolving about an axis, is employed to regulate the valve or "throttle," as it is termed, of the engine, one object of such invention being to relieve such balls and arms of the strain and labor now devolving upon them. Another object of the invention is to so construct the governor that it shall be very sensitive to the action of the steam, and change the valve quickly, in manner and to operate substantially as hereinafter explained.

In the drawings before mentioned, A denotes a hollow base or dome applied to the steam-chest in the proper position for admitting steam thereto, the steam entering such dome by apertures, a a , made in one side of such dome, and communicating with the steam-pipe leading from the boiler. The valve is shown at b as overlapping the exterior of the ports a a , the stem c of such valve extending across the interior of the dome and through its opposite sides, and being provided at its outer extremity with a vibrating sectoral lever, d , having a slot or opening, e , made through its upper part, a toothed rack, f and g , being formed upon the upper and lower boundary of such slot. A toothed pinion, h , plays within such slot, and is fixed to the outer end of a shaft, i , which is supported by and revolves in a horizontal vibrating hollow arm or bracket, k , the inner end of such bracket being pivoted to an arched standard or frame, l , rising upward from the top of the dome in such manner as to permit of vertical vibrating movements of the shaft i and its pinion h .

The shaft i is put in revolution by a spur-gear, m , fixed to its inner end, which engages with a second spur-gear, n , fixed to the extremity of a horizontal shaft, o , which extends across and above the dome A, and through opposite sides of the arch l , in which it is supported, the opposite end of such shaft o being provided with a pulley, which is operated by a belt leading directly from the main shaft of the engine, this last thus becoming the driving-shaft of the governing mechanism. A vertical shaft, q , revolves within a standard or goose-neck, r , rising from the top of the arch l , this shaft q having the usual regulator-balls and sliding sleeve, the latter shown at s in the drawings, applied to it in the ordinary manner, the shaft q being put in revolution by means of a bevelled gear, t , fixed upon its lower end, which meshes into a second bevelled gear, u , fixed upon the driving-shaft o , as shown in fig. 3 of the drawings.

A vibrating-lever, v , is pivoted at about its centre to the outer extremity of the goose-neck r , and has its inner end w extending into the groove x of the sliding sleeve s before mentioned. The outer end y of the lever v is connected to the outer extremity of the vibrating-bracket k before referred to by a pitman, z , and so that any vertical movements of the lever v shall produce corresponding movements of such bracket k . The slot e of the sectoral lever d is not in a circle struck from the centre of the axis of such lever, but is eccentric therewith, in order to follow the vertical vibrations of the pinion h , the said slot furthermore having an enlargement, a^1 and a^2 , at each end, in order to allow the vibrating-lever d to remain stationary under certain conditions, and not to be actuated by such pinion.

The regulating-valve b of the apparatus consists of a metallic disk, having segmental notches b' b' cut from its circumference, leaving gates c' c' upon opposite sides to work in conjunction with the ports or apertures a a before alluded to. These ports, as shown in fig. 4 of the accompanying drawings, are pointed or tapering at their extremities in order to shut off the steam gradually to some extent, and thus prevent sudden concussion or chucking of the engine under high pressure of steam.

The operation of the above-described mechanism is as follows: Taking as a starting-point the position of

the parts, as shown in fig. 1 of the drawings, that is, with the pinion h in engagement with the lower sectoral rack g of the lever d , and with the steam-ports leading to the dome A half open, or thereabouts, and with the engine increasing in speed; should the engine increase in speed at too rapid a rate, the continued rising of the regulator-balls (and consequently the sleeves) by means of the sleeve depresses the outer end of the lever v and maintains the pinion h in engagement with the rack g , it being understood that the driving-pulley is revolving in the direction indicated by the arrow thereon, which consequently drives the pinion in the opposite direction, or that shown by its arrow. This revolution of the pinion will move the sectoral rack d in the same direction and actuate the valve in such manner as to partially or wholly close the ports $a a$, and consequently diminish or cut off the entrance of steam to the dome A and the engine, and reduce the speed of such engine.

Should the engine be decreasing in speed to too great an extent, the lowering of the regulator-balls will raise the pinion h into engagement with the upper rack f , and by moving the sectoral lever d in the opposite direction, or that of the red arrow thereon, will open the valve, or the apertures $a a$, and admit more steam to the engine. The pinion h at times, and under certain conditions, (according to the pressure of steam and amount of labor demanded of the engine,) may travel to one or the other extremity of the slot e and remain there for a short time, or during an even movement of the engine. If it happens to be within the recess marked a^1 , (in which case the valve-ports will be wide open,) it will remain there until the movement of the engine has acquired too great speed, in which event the rapid revolution of the balls will lower the pinion h into engagement with the lower rack g , and consequently move the lever d in the direction of the black arrow, and, as before observed, diminish the amount of steam. *Vice versa*, should the pinion be within the space a^2 and the speed of the engine require accelerating, the lowering of the regulator-balls will throw the pinion into engagement with the upper rack f and move the lever d in the direction of the red arrow with the effect before stated.

It will be seen by the above description, which, though rather voluminous, is necessary to a complete understanding of the invention, that the only labor required of the revolving balls is to raise and lower the pinion h into engagement with one or other of the racks $f g$, as the revolutions of such pinion and vibrating movements of the sectoral lever are produced directly and entirely by the driving-shaft o . The apparatus is a very sensitive one, detecting and answering instantly the slightest variations in the speed of the engine. As perfect control is had over the movements of the engine, and it neither exceeds nor falls below its desired speed, no steam is wasted. As the pinion h revolves with speed, it produces a comparatively instantaneous change in the valve or much quicker than would be the case if the slow vertical movements of the balls and sleeve were depended upon, as heretofore, to accomplish this end.

The invention, although described above as a steam-engine governor, possesses advantages which render its application valuable as a governor or regulator for water-motors and for other purposes.

I have contemplated employing two pinions, combined with the vibrating shaft i , and operating with one rack in place of one pinion and two racks, as shown in the present instance. This, however, would not alter the character of this portion of my invention, which is intended to embrace the employment of a rack and pinion for operating the valve in connection with the usual regulator-balls.

I claim as my invention, and desire to secure by Letters Patent of the United States—

1. The combination of the valve-stem and sectoral rack or lever with the vibratory arm k , pinion h , and shaft i , receiving motion directly from the driving-shaft o , substantially as and for the purposes shown and set forth.

2. The combination of the valve-stem, the sectoral rack or lever, and its actuating-pinion and vibratory shaft of the gear $m n$, shaft o , and lever v , link z , and sleeve s , substantially as and for the purposes herein shown and specified.

3. I also claim the construction of the sectoral lever d , as composed of the eccentric-slot e , with its enlargements $a^1 a^2$ and its toothed racks f and g , essentially as before set forth and explained.

4. I also claim the combination, with the arch l , of the vibrating-arm or bracket k , the shaft i and the gears m and n , the bracket being pivoted to the arch, as before explained.
